UNITED STATES PATENT OFFICE.

FRANK B. YINGLING, OF HAMILTON, OHIO, ASSIGNOR TO COLUMBIA MACHINE TOOL CO., OF HAMILTON, OHIO, A CORPORATION OF OHIO.

SHAPER.

Application filed March 19, 1920. Serial No. 367,221.

To all whom it may concern:

Be it known that I, FRANK B. YINGLING, a citizen of the United States, residing in Hamilton, Butler County, Ohio, have invented certain new and useful Improvements in Shapers, of which the following is a full, clear, concise, and exact description, reference being had to the accompanying drawings, forming a part of this specification.

10 My invention relates to improvements in shapers and is especially concerned with the provision of means for supporting and adjusting the position of the work table so as to bring any one of a plurality of its faces 15 into the field of operation of the cutting tool.

The objects of my invention are—

First: To provide a shaper construction of the type referred to, comprising means for rotatably supporting the work table so 20 that any one of a plurality of its faces may be brought into position to hold work in the proper position relative to the cutting tool.

Second: To provide means of the character described, comprising means whereby 25 the work table can be adjusted both vertically and horizontally, irrespective of its angular adjustment.

Third: To provide a shaper of the construction referred to, in which both ends of 30 the work table are rigidly supported, and

Fourth: To provide means of the character described comprising a rail and a guide co-acting therewith for supporting the outer end of the work table, and permitting of its 35 horizontal adjustment, so constructed as to protect the sliding faces from chips which would tend to cause inaccuracy in cutting.

These and other objects will definitely appear as the description progresses, reference 40 being had to the accompanying drawings, in which—

Figure 1 is a side elevation of my improved shaper, certain portions thereof being omitted.

Figure 2 is an end elevation of my improved work table, and

Figure 3 is a view partially in section, and partially in side elevation, showing the details of construction of my improved work 50 table, certain parts thereof being broken away.

Throughout the several views, similar reference characters will be used for referring to similar parts.

55 Referring to the drawings, reference char-

acter 1 indicates the column of a shaper having a sole plate 2, the forward end of which extends outwardly beyond the end of the work table as will be referred to later on. Reference character 3 indicates the usual ram. Reference character 4 indicates the rail mounted, for vertical adjustment in the usual manner, upon which is slidably mounted the saddle 5 which can be adjusted in a horizontal plane in the usual manner.

60 The parts thus far described are merely conventional and may be modified, as desired.

Secured to the outer face of the saddle 5 by means of the screws or bolts 6 is a hollow cylindrical boss 7 provided with the spaced cylindrical bearings 8 and 9, and having the gear ring segment 10 formed thereon intermediate the two bearings. A pinion 11 is 65 mounted upon a shaft 12 journaled in the work table, the outer end of the shaft 12 projecting through the forward end of the work table and being angularly conformed, as shown at 13, to receive the socket of a wrench. By rotating the pinion 11, the work 70 table can be angularly adjusted about its axis so as to bring any one of the three of its faces into the field of operation of the cutting tool.

75 The lower edges or corners of the central work face are beveled, as shown at 13', to provide stops for limiting the rotation of the work table about its axis, these stops being adapted to co-act with the stops 13'' of the bracket 18. A set screw 14' co-acts with 80 the bearing 8 to lock the work table in its adjusted position.

85 For the purpose of supporting the outer end of the work table to prevent deflections or vibrations thereof, and consequent inaccuracy in the work, I provide a standard 14 which is secured to the outer extended end of the sole plate 2, as referred to above. This standard is provided with a pair of 90 vertical spaced guideways 15 for receiving the bolts 16, by means of which the horizontal rail 17 can be vertically adjustably mounted upon the standard 14. The rail 17 95 slidably supports the bracket 18 which is secured to the outer end of the boss 7 by means of the screws 19 or in any other desirable manner, the inner face of the bracket 18 being provided with a cylindrical boss 20 fitting within the open end of the boss and 100 providing a firm support for the same.

105

110

It will be noted that the bottom of the bracket is so formed, as shown at 18, as to completely cover the rail 17 and is somewhat longer than the rail 17, as a result of which 5 the rail 17 is protected against chips which might otherwise lodge on this rail and cause inaccuracy in the adjustments of the work table. I also provide a slide 21 which is secured to the lower end of the bracket 18 by 10 means of screws 22, or in any other desired manner, which co-acts with the lower face of the rail 17 to secure the bracket 18 rigidly to the rail 17. The circular edge 25 of the bracket 18 may, if desired, be provided with 15 a graduated scale to indicate the angular adjustment of the work table.

While I have described the details of the preferred embodiment of my invention, it is to be clearly understood that my invention is 20 not limited to these details, but is capable of other adaptations and modifications within the scope of the appended claims.

Having thus described my invention, what I claim is:

- 25 1. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.
- 30 2. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.
- 35 3. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.
- 40 4. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.
- 45 5. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.
- 50 6. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.
- 55 7. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support.

combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide longitudinally movable on the rail; and means for securing the work-table in adjusted rotative position on the support, the support and work-table being formed with cooperative stops adapted to stop rotation of the work-table in predetermined positions.

4. In a machine of the class described, the combination of a base; a column on the base; a support projecting outwardly from the column and vertically and transversely adjustable thereon; a work-table rotatively adjustable on the support; a standard on the base beyond but closely adjacent the outer end of the support and work-table; a transversely extending rail vertically adjustable on the inner side of the standard and disposed under the work-table, the support being provided with a fixed slide engaging the upper, under and inner side surfaces of the rail; and means for securing the work-table in adjusted rotative position on the support, the support and work-table being formed with cooperative stops adapted to stop rotation of the work-table in predetermined positions.

5. In a machine of the class described, the combination of a column, a rail vertically adjustable thereon, a saddle horizontally adjustable on the rail, a support projecting from the saddle, a standard adjacent the outer end of the support, a second rail vertically adjustable on the standard, a member rigidly secured to the outer end of the support and slidably engaging the second rail, and a work-table rotatably mounted on the support, said member and work-table being formed with engaging surfaces adapted to stop rotation of the work-table in predetermined positions.

In witness whereof, I hereunto subscribe my name this 10 day of March, 1920.

FRANK B. YINGLING.
